UNITED STATES PATENT OFFICE.

HENRY G. VOIGHT, OF NEW BRITAIN, CONNECTICUT.

ADJUSTMENT FOR DOOR-CONTROLLING MEANS.

1,070,363.

Specification of Letters Patent.

Patented Aug. 12, 1913.

Application filed October 21, 1912. Serial No. 726,925.

To all whom it may concern:

Be it known that I, HENRY G. VOIGHT, a citizen of the United States, residing at New Britain, county of Hartford, State of Connecticut, have invented certain new and useful Improvements in Adjustments for Door-Controlling Means, of which the following is a full, clear, and exact description.

This invention relates to controlling means for sliding doors in which a toggle is employed connecting the door to its casing or to a stationary abutment, which toggle must be of a definite length in order to be most effective.

It is my object to provide door controlling means of this character with an adjustment for the toggle whereby the same may be adjusted to a nicety in compensation for errors in manufacture and also in case of appreciable wear. Indeed, by my invention, the necessity for such absolute accuracy in measurements is obviated.

For the purposes of illustration I will describe and illustrate the application of the invention to the specific door controlling means of my Patent No. 1,041,706, dated October 15, 1912.

The adjustment means forming the subject matter of the present invention is more fully described in the detailed specification following and is illustrated in the accompanying drawings forming part thereof and showing a preferable embodiment of such adjusting means.

In these drawings: Figure 1 is a fragmentary view in elevation illustrating the adjustment means used in connection with a specific form of door controlling means employing a toggle. Fig. 2 is a top plan view illustrating the adjustable pivot connection of the toggle levers. Fig. 3 is a front elevation of the parts shown in Fig. 2. Fig. 4 is a detail view illustrating in front elevation and longitudinal section, the construction of the outer face of the forward toggle lever. Fig. 5 is an enlarged detail view of the forward end of the rear toggle lever. Fig. 6 is a detail view in front and end elevations of a clamping plate. Fig. 7 is a detail view in front elevation and top plan of a clamping washer. Fig. 8 is a detail view in side and end elevation of the pivot stud.

Referring to the drawings by numerals, 1 designates the forward edge of a sliding door and 2 the rear edge of the coöperating

door casing. A lever member 3 formed of complementary spaced bars 3^a is pivoted at its forward end to the forward edge of the door 1. A second lever member 4 formed preferably of complementary joined bars 4^a is pivoted to the rear edge of the door casing. Extending transversely of this second lever member 4 adjacent its rear pivoted end is a transverse arm 6. A power cylinder 7 is pivotally mounted at its lower end on the bracket 5 and has its piston 8 journaled in the lower end of the transverse arm 6, the power in the cylinder 7 normally tending to pull the piston rod 8 downwardly thereby pulling the lever member 4 downwardly with it. An operating handle 9 is pivotally mounted at 10 upon the forward edge of the sliding door 1. An arm 11 is pivotally mounted at 12 upon the forward edge of said door at a point below the pivot point 10 of the operating handle, and is provided with a curved slot 13 therein. A stud 14 carried by the bars 3^a of the lever member 3, engages said arm 11 and rides in its slot 13, which slot owing to its curvature, acts as a cam to raise lever member 3, when said arm is moved. The arm 11 is provided, adjacent its pivoted end, with a curved slot 15 therein, describing an arc with the pivot point 12 as a center and a stud 16 carried by the operating handle 9 rides in this slot and is adapted, when the handle is moved to the right from the position shown in Fig. 1, to move arm 11 and thereby raise lever member 3 through the cam action of slot 13 on stud 14. The lever members 3 and 4 have their rear and forward ends respectively, pivotally connected so that the force of the power cylinder 7 will act through its piston rod 8 arm 6 and lever member 4, to move the sliding door 1 forwardly to closed position, straightening out the toggle formed by the lever members 3 and 4, as the door reaches closed position, so that these lever members are in horizontal alinement with their connecting pivot on a dead center with these lever members. This, when the lever components are properly proportioned, will afford a dead center lock against accidental door opening movement on the part of these levers. The door may be opened by moving the operating handle to the right from the position shown in Fig. 1, this movement causing the arm 11, through its cam slot 13, to raise lever member 3 and break the toggle lock, this movement being permitted by rea-

son of the fact that a limited free movement of the handle 9 independent of the door is possible. At the end of this limited free movement, the toggle lock will have been 5 broken and the handle 9 will strike against an abutment stud 17 so that a further pull on the handle 9 in the same direction will move the door itself to open position against the force of the power cylinder 7.

10 I do not claim herein the specific form of operating means and toggle lever connection, described, as this forms the subject matter of my Patent No. 1,041,706, dated October 15, 1912, the present invention consisting in 15 the application in combination with operating means of this general character, of the toggle lever adjustment means which will now be described in detail.

20 This adjustment of the toggle to secure the definite lever components requisite to successful operation, is, in the present instance, accomplished by providing an adjustable pivot connection between the two 25 lever members forming the toggle. To this end I provide a pivot stud 18 having an enlarged hub portion 19 formed thereon intermediate its ends. The forward ends of the 30 bars 4^a of the lever member 4 are adapted to be journaled on this hub portion, these bars being provided with alined apertures 20 therethrough. The hub portion 19 is of 35 greater thickness than these joined bars 4^a so that it will project slightly beyond the opposite faces of the joined bars (see Fig. 2). The shank of the pivot stud 18 on 40 either side of the hub portion 19, is screw threaded as at 21 and 22 respectively, the shank portion 22 being preferably of somewhat greater length than the shank portion 21. The pivot stud at the end of the single 45 portion 22 is provided with a slot 23 to receive the head of a screw driver or other suitable tool. Each of the bars 3^a forming the lever member 3, adjacent their rear ends are provided with alined elongated slots 24 through 50 which the shank ends of the pivot stud 18 extend to project beyond the outer faces of said bars. The forward apertured end of the joined bars 4^a is brought between the rear ends of the forward lever bars 3^a, so that the apertures 20 and the slots 24 are in alinement. The pivot stud 18 is then inserted through the alined apertures so that its hub portion 19 is seated 55 within the apertures 20 of the joined bars 4^a with the end faces of said hub portion projecting slightly beyond the outer faces of these bars and abutting against the inner faces of the spaced bars 3^a. A detachable 60 clamping plate 25 rests against the rear face of the rear bar 3^a and is provided with a boss 26 and with a threaded aperture 27 extending through said plate and boss, this threaded aperture being engaged by the 65 threaded shank 21 of the pivot stud, and

being drawn against the rear face of the rear bar 3^a when said pivot stud is rotated by a screw driver or other suitable tool. The front face of the front bar 3^a is provided with a series of transverse corrugations 28 surrounding and extending beyond the elongated slot 24 therein. A washer 29 provided on its rear face with similar corrugations 30, is centrally apertured to fit over the threaded shank 22 of the pivot stud to engage the corrugations 28. A nut 31 is then screwed up on the threaded shank end 22 to clamp this washer against the outer face of the outer bar 3^a, the pivot stud being held stationary of course, while the nut is being screwed up. Owing to the fact that the end faces of the hub 19 extend beyond the outer faces of the joined bars 4^a, the bars 3^a are spaced slightly from the bars 4^a which, therefore, may be turned on the hub 19 and are not clamped against movement by the clamping engagement of the plate 25 and washer 29. As the bars 3^a are clamped against the end faces of the hub 19 by the means described, the hub 19 is of course, held stationary.

70 It will be seen that by reason of the structure described, the point of pivotal connection between the front lever member 3 and rear lever member 4 may be moved to meet the exigencies of the particular case and the clamping plate 25 and washer 29 moved into clamping engagement with the bars 3^a to fixedly maintain the pivot point as moved and adjusted. The length of the elongated 75 slots 24 will be such of course, as to provide plenty of adjustment in both directions. Also while the lever member 4 has been shown and described as being comprised of joined bars 4^a, it is obvious that it may be 80 formed of a single bar of sufficient thickness and strength to meet the service conditions of the particular case, the width of the hub member 19 being of course, modified to suit the thickness of the particular lever bar 85 110 115 120 125 130

In the preferred construction, the arm 3 is preferably somewhat longer than the arm 4, which is common practice, and is disclosed in my former patent above referred to. In 115 the preferred construction, also I provide the adjustment slot in the longer arm 3 so that when the device is adjusted to meet the different conditions encountered in the installation of the apparatus in different 120 buildings, where conditions almost always vary, the change in the pivot point will occur with reference to the length of the longer arm 3, it being always preferable to have the arm 4 never of greater length than the arm 3, and ordinarily of less length because, as is well known, if the arm 4, to which the closer mechanism 7 is attached, is unduly long, it may permit the other arm to rise to such a steep angle as to impair the 125 130

efficiency of the closer in its action on the door in a closing direction. Again, it is preferred to have the arms so nearly of equal length that it is not possible for the 5 arm 4 to be made so short as to exert such a leverage as to make it difficult for the operator of the elevator to swing up the arm 3 in the act of opening the door. The best results, therefore, can be obtained by 10 providing the slots 24 in the longer arm 3.

From the foregoing, it will be evident that I have provided in combination with a door controlling mechanism of the general character illustrated, means for varying and 15 adjusting the components of the toggle to secure the most effective operation of a device of this character.

While I have herein described and shown a specific embodiment of the invention and 20 illustrated it as applied to a particular type of door controlling means, I desire it understood that the invention is not limited to this specific combination, but that the specific structure employed may be modified 25 within the spirit of the invention and the scope of the appended claims.

What I claim is:

1. Connecting means for use between sliding 30 closures and relatively stationary abutments, embodying a toggle comprising two pivotally interconnected bars, and means for varying the over-all length of said bars, at the point of pivotal connection of one bar relative to the other.

35 2. Connecting means for use between sliding closures and relatively stationary abutments embodying a toggle of two pivotally interconnected bars, one of said bars being provided with a pivot stud adjustable longitudinally thereof, and the other of said bars being journaled on said stud.

40 3. Connecting means for use between slid-

ing closures and relatively stationary abutments embodying a toggle comprising two pivotally connected levers, one of said levers 45 having an elongated slot therein, a pivot stud insertible through said slot and adjustable longitudinally thereof, the other of said levers being journaled on said pivot stud.

4. Connecting means for use between sliding 50 closures and relatively stationary abutments, embodying a toggle, said toggle comprising a lever having complementary spaced arms provided with elongated aligned slots therein, a pivot stud carried by said complementary arms and extending through the slots therein, a second lever having its end extending between said spaced arms and journaled on said pivot stud, and means for varying the position of said stud in said 55 elongated slots and for clamping said stud rigidly to said spaced arms whereby the range of movement of said toggle may be varied.

5. Connecting means for use between sliding 60 closures and relatively stationary abutments, embodying a toggle, said toggle comprising a lever member having complementary spaced arms provided with elongated aligned slots therein, a stud carried by 65 said arms extending through the slots therein and having a hub formed thereon between said arms, a second lever having its end extending between said spaced bars and journaled on said hub, and means whereby the 70 relative position of said stud in said elongated slots may be varied and whereby said spaced bars may be clamped against said hub to hold said stud rigid relative thereto.

HENRY G. VOIGHT.
